UNITED STATES PATENT OFFICE.

FRANK BRALLIER, OF JOHNSTOWN, PENNSYLVANIA.

IMPROVEMENT IN NUT-LOCKS.

Specification forming part of Letters Patent No. **179,994**, dated July 18, 1876; application filed June 12, 1876.

To all whom it may concern:

Be it known that I, FRANK BRALLIER, of Johnstown, in the county of Cambria and State of Pennsylvania, have invented certain new and useful Improvements in Nut-Locks, of which the following is a specification:

Figure 1 is a top plan view. Fig. 2 is a partly vertical central section, and partly perspective.

This invention relates to a device for securing a locking-nut in its position on the threaded end of a bolt, so that it cannot be rattled or shaken out; and it consists more particularly in providing the nut with a key embedded in it, having an inclined face and operated by a spring to engage in vertical grooves or recesses in the bolt-shaft, so that while the key will readily slide over the thread and grooves as the nut is being turned down, an opposite motion will be prevented by the inner end of the key taking into the grooves, all as will now be more in detail set out and explained.

In the drawings, A denotes the nut, having in a suitable socket, a, the key A', adapted to be automatically operated by spring a'. The vertical inner face of the key is inclined from left to right, and thus adapted to seat itself snug in the angular vertical grooves b b (one or more) in the outside of the shaft of the bolt B, when, in the movements of the nut on the bolt, the two come into conjunction. When the nut is being turned down on the bolt the spring behind the key allows the key to move back sufficiently to give a clear inner diameter to the nut, and allow the key to slide easily upon the upper surface of the screw-thread on the bolt; there is, consequently, no difficulty in turning the nut down. The opposite motion is securely prevented by

the engagement of said key in one of the vertical grooves; but if for any cause it shall be desired to turn the nut in the opposite direction, it can be done by pulling the key back by means of pin a'', which projects through a suitable orifice in the side of the nut. This pin or handle also serves to guide and steady the key in its movements, and also in good measure to hold it and its spring in the nut when the nut is taken off the bolt. This nut cannot be shaken or jolted out of its place, because no motion of it will serve to throw the key out of its engagement with the groove, nor will any such motion of the bolt conduce to this end. The key and spring, being embedded in the nut, are held in a strong and safe seat, free from all harm or accident. The pin may be constructed as now shown, or be shortened or otherwise conveniently made and adapted so as not to be inconvenient for use or unsightly to look at.

Having thus described my invention, what I claim as new, and desire to secure by Letters Patent, is—

The combination of a nut, having an apertured recess, a reciprocating key resting in the recess with a guide and handle projecting through the aperture of the recess, a spring acting against the key and the opposing side of the recess, and a vertically-grooved bolt, as and for the purposes specified.

In testimony that I claim the foregoing as my own I affix my signature in presence of two witnesses.

FRANK BRALLIER.
